(57) **CLAIM**

The ornamental design for a console for automobile, as shown and described.

DESCRIPTION

FIG. 1 is a perspective view from the left side of a console for automobile.

FIG. 2 is a perspective view from the right side thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof.

FIG. 8 is a referential perspective view with the armrest portion slid.

FIG. 9 is a referential perspective view from the left side with the armrest portion opened; and,

FIG. 10 is a referential perspective view from the right side with the armrest portion opened.

The portions of the console shown in broken lines are for the purpose of showing environmental structure only and form no part of the claimed design.
